UNITED STATES PATENT OFFICE.

CHRISTFORE M. AUGUSTINE, OF LINDEN, NEW JERSEY, ASSIGNOR TO SIMMONS COMPANY, OF NEW YORK, N. Y., A CORPORATION OF DELAWARE.

DESIGN FOR A BEDSTEAD END FRAME.

Application filed March 19, 1925. Serial No. 12,771. Term of patent 14 years.

To all whom it may concern:

Be it known that I, CHRISTFORE M. AUGUSTINE, a citizen of the United States, and a resident of the city of Linden, county of Union, and State of New Jersey, have invented a new, original, and ornamental Design for Bedstead End Frame, of which the following is a specification, reference being

had to the accompanying drawing, forming part thereof.

The figure is a perspective view of a bedstead end frame showing my new design.

I claim:

The ornamental design for a bedstead end frame as shown.

CHRISTFORE M. AUGUSTINE.
